United States Patent Office.

ISAAC BANISTER, OF NEWARK, NEW JERSEY.

Letters Patent No. 62,306, dated February 26, 1867.

IMPROVED SHOE-CLASP.

The Schedule referred to in these Letters Patent and making part of the same.

TO ALL WHOM IT MAY CONCERN:

Be it known that I, ISAAC BANISTER, of the city of Newark, in the State of New Jersey, have invented a new and improved Clasp to take the place of strings, buttons, or other fastenings for shoes, gaiters, or other articles of dress or clothing; and I do hereby declare that the following is a full and exact description thereof, reference being had to the accompanying drawings, and to the letters of reference marked thereon.

The nature of my improvement consists in so forming two plates or narrow strips of flexible metal that they form a clasp, as represented in the accompanying drawings.

Figure 1 represents the clasp open. A is the upper or face plate; B is the under or back plate; C is the hinge connecting the two plates, formed by perforating the plate B at C and inserting the plate A, made narrow to fit the hole in B, and bent up to form the hinge C; E E are holes made in the under plate B to fasten it.

Figure 2 shows a longitudinal section of the clasp closed. The under plate B is bent up and over toward the hinge to form a catch at D, the end of B rounded and concave from beneath, and A bent up to fit in the cavity, as at D. To open the clasp requires a side pressure of A at D.

What I claim, and desire to secure, is—

A clasp, when formed substantially in the manner and for the purposes set forth.

ISAAC BANISTER.
